DESIGN FOR A SCORE PAD HOLDER

Gordon Tucker, Minneapolis, Minn.

Application March 4, 1946, Serial No. 127,078

Term of patent 7 years

(Cl. D34—5)

To all whom it may concern:

Be it known that I, Gordon Tucker, a citizen of the United States and residing in the city of Minneapolis, county of Hennepin, State of Minnesota, have invented a new, original, and ornamental Design for Score Pad Holder, of which the following is a specification, reference being made to the accompanying drawing, forming a part thereof, wherein:

Fig. 1 is a front elevation of a score pad holder showing my new design;

Fig. 2 is a top plan view of the same; and

Fig. 3 is a side elevation.

I claim:

The ornamental design for a score pad holder, as shown.

GORDON TUCKER.
